UNITED STATES PATENT OFFICE.

HARRIET BATTESSE DAWKINS, OF CHARLOTTE, NORTH CAROLINA, ASSIGNOR OF ONE-HALF TO JAMES E. DAWKINS, OF CHARLOTTE, NORTH CAROLINA.

COLLAPSIBLE FOOT-MEASURING DEVICE.

1,356,489.

Specification of Letters Patent. Patented Oct. 19, 1920.

Application filed November 25, 1919. Serial No. 340,520.

To all whom it may concern:

Be it known that I, HARRIET BATTESSE DAWKINS, a citizen of North Carolina, U. S. A., residing at Charlotte, in the county of Mecklenburg and State of North Carolina, have invented new and useful Improvements in Collapsible Foot-Measuring Devices, of which the following is a specification.

10 This invention relates to measuring devices, particularly to those designed for use by the shoe dealers for measuring a foot to determine the proper size shoe therefor, and has for its object the provision of a foot measuring device which is formed of a plurality of slidably connected sections whereby the device may be readily extended for use or collapsed so as to occupy but little space so that it may be carried in the pocket 15 of the salesman, one end portion of the device being formed as a receptacle which inclosingly receives the remaining sections when in collapsed position, certain of the sections being graduated in shoe sizes.

20 An important object is the provision of a device of this character which will be simple and inexpensive in manufacture, highly efficient in use, durable in service, and a general improvement in the art.

25 With the above and other objects and advantages in view, the invention consists in the details of construction to be hereinafter more fully described and claimed, and illustrated in the accompanying drawings in which—

Figure 1 is a plan view of the device in extended position,

Fig. 2 is a side elevation thereof,

Fig. 3 is a longitudinal sectional view 40 illustrating the slidable connection of the sections,

Fig. 4 is a cross sectional view,

Fig. 5 is a detailed perspective view of the heel engaging end section,

Fig. 6 is a perspective view of the device 45 in collapsed position, and

Fig. 7 is a cross sectional view there-through.

Referring more particularly to the drawings, I have shown my device as comprising an end section 10 which is formed as a hollow body having one edge open and cut away, as shown at 11, with this cut away portion provided with a recess 12 at each 55 side of the device. Disposed within and

adapted to extend beyond the open edge of this hollow section, is a plate section 13 which has at its rear corners bearing members 13^a slidably engaging within guide slots 13^b in the member 10 and which has 60 its side edges formed with guide slots 14. Slidably connected with this plate section 13 is a section 15 which is the endmost one of a plurality of similar sections 16, 17, 18 and 19 all of which are provided at their 65 edges with guide slots 20 similar to the guide slots 14 and the successive sections have at their edges, bearing members 21 slidably engaging the guide slots 20, yet this connection is such that when the sections are in 70 extended position, as shown in Figs. 1 and 2, the device will possess proper rigidity so as to avoid buckling. Slidably connected with the section 19 is a section 22 which is provided with laterally extending ears 23 75 at its ends and which is provided upon one face with an upstanding projection 24 having an arcuate face 25. This curved face 25 is adapted to be engaged by the heel of the foot to be measured.

80 The sections have inscribed thereon longitudinal lines 26 across and beyond which extend transverse lines 27 which designate the whole sizes of shoes, and between these transverse lines 27 are other transverse lines 28 indicating the half sizes. At the ends of the transverse lines 27 are inscribed numerals indicating the sizes while each transverse line 28 has inscribed adjacent thereto the legend “½.”

85 In the use of the device it will be seen that when the parts are in extended position, as shown in Figs. 1 and 2, the customer places his foot upon the extended sections with his heel engaging the curved face 25 95 of the projection 24. At whatever transverse line 27 or 28 the toe of the foot terminates will indicate the proper shoe size. These shoe scales are in themselves well known and the present device does not claim 100 novelty in this particular, the novel features being the collapsible sections. When the use of the device is not desired, it will be seen that by pressing against the endmost sections 10 and 22, all the sections will slide 105 one upon the other and they will all be disposed within the hollow section 10 with the outer straight face of the section 22 forming a closure for the hollow section 10. The laterally projecting ears 23 on the section 110

22 are for the purpose of affording a grip whereby the section 22 may be grasped to pull all the sections out of the section 10 and the recess 12 is also for the purpose of 5 permitting a grip on the section 22. It will be observed that the sections 15, 16, 17, 19 and 22 are of progressively increasing length so as to compensate for the thickness of the bearing members 21 so that all the 10 sections will fit snugly within the hollow section 10.

From the foregoing description and a study of the drawings it will be apparent that I have thus provided a simple and efficient device which may be readily extended for use in measuring a foot to determine the shoe size and which may be readily collapsed into small compass for convenience in storage within the pocket.

20 While I have shown and described the preferred embodiment of my invention, it is of course to be understood that I reserve the right to make such changes in the form,

construction, and arrangement of parts as will not depart from the spirit of the invention or the scope of the subjoined claim.

Having thus described my invention, I claim:

A device of the character described comprising a plurality of slidably connected sections each formed as a plate having near its lateral edges guide slots and the adjacent plate carrying bearing members engaging said slots, one endmost section being formed hollow to serve as a container for the other sections when collapsed, and the other endmost section serving as a closure for the first named endmost section, a projection on said second named endmost section having a curved face for engagement by the heel of a foot, and the intermediate sections being inscribed with graduations indicating shoe sizes.

In testimony whereof I affix my signature.

HARRIET BATTESE DAWKINS.
